CLAIM

The ornamental design for a solid fuel cooking device including polygonal shaped upper body, as shown and described.

DESCRIPTION

FIG. 1 is a perspective view of a solid fuel cooking device including polygonal shaped upper body with the cover portion attached showing my new design;

FIG. 2 is a perspective view of the solid fuel cooking device including polygonal shaped upper body with the cover portion attached shown removed from the environmental structure for clarity of illustration;

FIG. 3 is a perspective view of the solid fuel cooking device including polygonal shaped upper body with the cover portion detached shown removed from the environmental structure for clarity of illustration;

FIG. 4 is a side view of the solid fuel cooking device including polygonal shaped upper body with the cover portion attached shown removed from the environmental structure for clarity of illustration;

FIG. 5 is a top view of the solid fuel cooking device including polygonal shaped upper body with the cover portion detached shown removed from the environmental structure for clarity of illustration; and,

FIG. 6 is a bottom view of the solid fuel cooking device including polygonal shaped upper body with the cover portion detached shown removed for the environmental structure for clarity of illustration.

The broken lines are included for the purpose of illustrating unclaimed portions of the solid fuel cooking device including polygonal shaped upper body as well as unclaimed environmental structure. The broken lines in the drawings form no part of the claimed design.
